PAPER BOTTLE

Henry J. Reiter, Philadelphia, Pa., assignor to
Brown & Bailey Company, Philadelphia, Pa.,
a corporation of Pennsylvania

Application November 15, 1939, Serial No. 304,475

5 Claims. (Cl. 229—17)

This invention relates to paper or cardboard bottles of the general type disclosed in United States Letters Patent 2,079,875 and 2,079,876 issued to me May 11, 1937, and is more particularly concerned with improving the leak-proof qualities of such bottles. These latter now customarily have a reinforcement of flexible sheet material glued to the upper part of their inner surface and a pouring opening in this reinforcement and the adjacent wall, with hinged superposed flaps defined by partly cutout portions of these parts cooperating to keep the opening sealed until the consumer wishes to use some of or all the contents of the bottle. Then the lower edge of the outer flap is first lifted away from the bottle wall and next pulled upwardly to progressively detach it therefrom until it lifts the inner flap out of the opening in the reinforcement after which by partially inverting the bottle the contents can be poured; to subsequently preserve any remaining portion of the contents the outer flap can be pressed down to initial position thereby again forcing the inner flap into the opening in the reinforcement to close the latter.

These bottles are manufactured by automatic machines in enormous quantities but although they have gone into wide-spread use it has been found that leakage of the contents sometimes takes place in the vicinity of the outer flap covering the pouring opening. This is very objectionable since when it occurs the contents, usually milk, tend to seep down the wall of the bottle below the flap and collect at its base, thus not only defacing the appearance of the bottle itself but rendering it sticky and unsanitary and defiling the refrigerator or other receptacle in which it is stored. But whether or not such leakage will occur in a given bottle cannot ordinarily be determined in advance of its being filled and sealed since the conditions which cause it are usually due to the bending of the material during the sealing operation. Moreover as the leakage takes place slowly it may not be evident, though none the less present, for several hours after the bottle is sealed and therefore in the hands of the retailer or even the consumer.

I have discovered this leakage results either from minute separation of the reinforcement from the bottle wall or from separation of the fibers of the material of which the reinforcement is made or from both, which enable the fluid contents of the bottle to travel inwardly from the lateral edge of the reinforcement to the vicinity of the outer flap and thence seep outwardly onto the surface of the bottle. This is because in the

method of constructing the bottles heretofore employed the reinforcement, in which the inner flap is formed, is scored toward its inner face, that is, from its outside toward its inside in the same direction that the other scores are made in the blank; the blank is then formed up and glued to produce the body of the bottle which is next waterproofed by dipping in liquid paraffine or similar material, thus placing it in condition for filling and subsequent sealing. During the sealing operation the reinforcement is bent transversely inwardly along an inwardly indented score line common to it and the blank proper and pulls away at this line from the surface to which it has been glued so that a channel is formed adjacent the fold line through which the fluid contents of the bottle can subsequently seep inwardly toward the flap and thence out of the bottle through the perforations defining the latter or else the fibers of the material of the reinforcement are separated internally by the strain set up in bending it so that the fluid can easily penetrate edgewise through the material itself with a like result. It is essential, however, that the flap which extends over the fold line to a point in the side wall of the bottle be defined in such way from the adjacent material, as by a suitable score line, that the extremity of the flap will tend to spring outwardly from the bottle so that a finger nail or the like can readily be inserted beneath it when it is desired to lift it, for if the construction is such as to cause it to hug the bottle the lifting of the flap becomes a too difficult and annoying operation for the consumer and thus detracts from the saleability of the bottle.

It is therefore an object of my invention to obviate this leakage by so constructing the bottle that the edge portions of the inner reinforcement are maintained in fluid-tight relation with the bottle walls at all times, especially in the areas in which they intersect the lines of fold of the latter, and that any tendency of the fibers of the material of which the reinforcement is made to separate internally and thus make it more than normally fluid-conductive is negated.

Another object is to provide the bottle with an outer flap for the pouring opening so arranged that whatever tendency it may have to separate from the bottle wall is exerted in the direction to facilitate the opening of the flap to thereby afford easy access to the bottle contents.

Other objects, purposes and advantages of the invention will hereinafter more fully appear or 55 be understood from the following description of

the preferred embodiment of it illustrated in the accompanying drawing, in which

Fig. 1 is a fragmentary front elevation of the upper part of the bottle after filling and sealing;

Figs. 2 and 3 are respectively fragmentary vertical sections on lines 2-2 and 3-3 in Fig. 1;

Fig. 4 is a fragmentary plan view of the blank from which the bottle is formed;

Fig. 5 is a fragmentary perspective view of the upper part of the bottle on a smaller scale than Fig. 1, and

Fig. 6 is a fragmentary sectional perspective view, generally corresponding to Fig. 2, of a bottle of the type heretofore employed.

In the several figures like characters are used to designate the same parts and in some, to facilitate explanation, the relative thickness of materials is considerably exaggerated.

The bottle of my invention shown in Figs. 1-5 is formed from the blank illustrated in Fig. 4 which comprises four side panels 1, 2, 3 and 4 arranged side by side and defined from each other by vertical scores 5, 6 and 7 and a glue lap 8 projecting from panel 4 and defined therefrom by a score 9. The side panels and glue lap respectively carry bottom flaps and a tab (not shown) which are folded inwardly to make the bottom of the bottle after the side panels have been folded in a hollow square and glue lap 8 glued to panel 1. The upper ends of the side panels and glue lap carry extensions 10-14 inclusive separated from these parts by a transverse score 15 beginning at a point 16 spaced from the free edge of panel 1 a distance substantially equal to the width of the glue lap and extending therefrom across the remainder of panel 1 as well as across panels 2, 3, 4 to merge into a "knife score" 17 in the glue lap. Score 15 where it crosses panel 2 is of special form as will be hereinafter more fully explained but scores 5, 6, 7, 9 and other scores in the extensions are substantially like those heretofore utilized in bottles of the same general type as exemplified by my said prior patents, being made by depressing the blank toward that surface which is to become the inside of the bottle; they therefore require no further description.

Extension 11 of panel 2 is further transversely scored at 20 and perforated at 21 to define a U-shaped hinged flap 22 extending from score 20 in the upper part of the extension to a point in panel 2 a short distance below score 15 where a recess 23 is cut out of the panel to afford convenient access to the edge of flap 22 preparatory to raising it. Underlying the general area in which flap 22 is formed is a reinforcement 24 of substantially the same material as the blank itself. This reinforcement is glued to the blank for some distance inwardly of its perimeter and has formed in it an inner flap 25 which is glued to outer flap 22 and defined from the rest of the reinforcement by a constricted U-shaped cut 26 and a transverse score 27 substantially coincident with hinge score 20 of the outer flap.

Referring now more specifically to the transverse score 15, it will be apparent from Fig. 4 that its character changes at the edges of panel 2 and also adjacent the edges of outer flap 22; that is, preferably on either side of flap 22 and between it and the edges of the panel convex scores 15a, 15b are formed in the blank and the reinforcement 24 by indenting the material from beneath as viewed in Fig. 4, instead of from above, which is the way the other scores in the blank are indented, for example scores 5, 6, 7, the intermediate portion 15c of score 15 where it crosses

flap 22 and the remainder of score 15 in the other panels. In other words, the last mentioned scores are so formed as to present convex ridges on the inside face of the blank and parts 15a, 15b of score 15 to present concave grooves.

As a result of this construction, when extension 11 of panel 2 is folded inwardly after the bottle has been filled, portions 15a, 15b of score 15 between flap 22 and the edges of the panel are bent toward the side from which they were indented and reinforcement 24 is therefore crowded into the corner formed by the panel and extension as clearly illustrated in Fig. 2 with consequent compacting of the fibers of the material. A fluid-tight joint is thus assured between the reinforcement and bottle wall at these points. Flap 22 is scored at 15c in the opposite direction, however, so its outer surface is slightly stretched during this bending, which induces in its lower part a slight tendency to spring outwardly away from reinforcement 24 thereby facilitating insertion of the finger nail or a suitable pointed instrument between these parts for opening the bottle. Thus while edges of the reinforcement are held tightly against the bottle wall at the corners formed by the panel 2 and its extension and leakage of the fluid contents at these points therefore positively inhibited, facility in opening the bottle is not impaired as would be the case were part 15c of score 15 made in the same way as parts 15a and 15b.

To demonstrate more clearly the manner in which my invention eliminates the disadvantage of the prior bottles to which I have referred, there is shown in Fig. 6 a fragmentary perspective section of such bottle. In this figure, corresponding generally to Fig. 2, the manner in which reinforcement 24' very frequently springs away from the corner formed by panel 2' and its extension 11' when these parts are bent up is clearly apparent, a horizontal generally arcuate channel 30 between the reinforcement and the bottle wall being thereby produced through which the contents can travel inwardly in opposite directions toward flap 22' and finally leak out around its edges. Sometimes, however, reinforcement 24' may adhere to the bottle wall so that no such channel is formed but instead the fibers of the reinforcement separate internally under the bending strain and the fluid contents then travel toward flap 22' through the reinforcement itself with resultant leakage of the bottle contents in a generally similar way. While in my improved bottle such separation of the reinforcement from the wall panel, or its internal separation, may likewise occur along score 15c in the area underlying outer flap 22, as indicated in Fig. 3, this area of the reinforcement is remote from its lateral edge portions which adhere tightly to the bottle and prevent the contents traveling inwardly to score 15c; separation of the parts or internal separation of the reinforcement in this area is of course immaterial from the standpoint of leakage.

It will thus be evident that after my improved bottle has been filled and its top folded and sealed as indicated in Fig. 5, flap 22 may readily be lifted outwardly to separate it on perforations 21 from adjacent wall extension 11 and then moved about the hinge formed by its score 20, inner flap 25, glued thereto and cut and scored from reinforcement 24, moving concurrently about its hinge score 27 to enable the contents of the bottle to be poured from the resultant opening. If it be desired to thereafter close the bottle the flaps are

merely pressed downwardly and under normal conditions the inner flap enters and is frictionally retained in the pouring opening from which it has been separated while the outer flap, by similar cooperation with the bottle wall, assists in keeping the opening effectively closed against contamination or the like.

While I have herein particularly described a preferred embodiment of the invention it will be understood that changes and modifications in the form, construction and arrangement of the several parts will occur to those skilled in the art and may be made without departing from the spirit and scope of the invention as defined in the appended claims.

Having thus described my invention, I claim and desire to protect by Letters Patent of the United States:

1. A paper bottle having a top closure and a wall panel, an extension integral therewith forming part of the top closure and defined from the panel by a score indented outwardly from the inner surface of the bottle, a hinged outer flap integral with and partially severed from the extension and panel, a reinforcement secured at its edge portions to the extension and panel and scored in conformity with the first mentioned score, a hinged inner flap partially severed from the reinforcement, secured to the outer flap and adapted to be raised therewith to expose a pouring opening, the reinforcement and outer flap having registering scores indented oppositely to said first mentioned score extending in prolongation thereof, said scored parts being folded angularly inward along said scores whereby said edge portions of the reinforcement are compressed against the panel and extension at the line of fold defined by said scores.

2. In a bottle formed of bendable sheet material, a panel having an integral extension, a reinforcement secured to said parts, and hinged inner and outer flaps partially severed from the reinforcement and from the panel and extension respectively and liftable about a common axis to expose a pouring opening, the extension and part of the reinforcement lying at an angle to said panel and to the remainder of the reinforcement and being defined therefrom by scores coincident with the vertex of said angle, the reinforcement having adjacent its edge a score indented toward the exterior of the bottle whereby the reinforcement is compacted proximate said score against the panel and extension at said vertex, the outer flap and underlying part of the reinforcement being scored in the opposite direction coincident with said vertex.

3. In a bottle, a wall panel formed of bendable sheet material, an integral extension project-

angularly from the upper edge of the panel, an outer flap conforming to the angularity of and partially severed from said parts and hinged to the extension adjacent a pouring opening, a reinforcement also substantially conforming to said angularity within the bottle, having its edge portions intimately secured to the panel and extension and compacted toward the vertex of the angle formed thereby, and an inner flap 10 partially severed from the reinforcement and secured to the outer flap to expose said pouring opening when the flaps are raised, the outer flap and reinforcement in the area between said compacted edge portions being bent inwardly away 15 from the vertex of said angle to thereby urge the extremity of the outer flap outwardly of the wall panel.

4. In a paper bottle, a plurality of wall panels and extensions respectively defined by scores indented in a common direction transversely of 20 the blank from which the bottle is formed, another panel with an extension defined therefrom in part by a score indented in the opposite direction to said scores and in part by a score indented 25 in the same direction; a reinforcement secured to and underlying the panel and extension and correspondingly scored coincident with the last mentioned scores whereby when the extension is bent about said last mentioned scores and toward 30 the reinforcement in sealing the bottle, the reinforcement is crowded toward the line of bending in the vicinity of said oppositely indented score, a flap being defined from said other panel and extension by a partial severing intersecting 35 the line of bend proximate the junctions of said oppositely indented scores and overlying the reinforcement, and a flap partially severed from the reinforcement and secured to the first flap.

5. In a blank for a paper bottle, a plurality of 40 wall panels and extensions respectively defined by scores indented in a common direction, another panel with an extension defined from it by scores indented in the opposite direction adjacent the lateral edges of the extension and by a score indented in the same direction intermediate 45 said edges, a reinforcement secured adjacent its edges to said other panel and extension, comprising parts defined from each other by like 50 scores whereby when the extension is bent relatively to the panel toward the reinforcement and along said scores the reinforcement is compacted adjacent its edges in the vicinity of said oppositely directed scores, a flap being defined in the panel and extension having edges intersecting the junctions of said oppositely indented 55 scores and another flap defined in the reinforcement and secured to the first flap.

HENRY J. REITTER.
